FOOTWEAR AND METHOD OF MAKING IT

Jacob S. Kamborian, West Newton, Mass.

Application March 18, 1944, Serial No. 527,101

4 Claims. (Cl. 12—142)

1

This invention relates to footwear and more particularly to a novel shoe of the welt type and to a method of making it. While of general utility, the present invention is especially valuable when, and is herein specifically illustrated, merely by way of example, as embodied in children's footwear. When made in accordance with customary prior procedures, children's shoes are often badly shaped and have foot-supporting surfaces which are so rough and uneven that they would not be tolerated by adults, and are thus rightly blamed for many of the foot defects of after years. A principal object of the present invention is to provide a shoe having a level, smooth and resilient foot-supporting surface and which has a properly shaped lasted upper and bottom; to provide a shoe, particularly a child's shoe, of good appearance and of good durability; and to provide a novel method of making welt shoes whereby shoes having the characteristics above suggested may be made cheaply and expeditiously and by relatively unskilled workers.

Heretofore it has not been deemed practical to make a shoe of the "California" or force-lasted type having a toe or heel stiffener. A further object of the present invention is to provide a method whereby a shoe of this general type may be provided with a toe or heel stiffener, or both.

Other and further objects and advantages of the invention will be pointed out in the following more detailed description and by reference to the annexed drawing wherein:

Fig. 1 is a plan view of a shoe vamp, especially the vamp of a child's shoe;

Fig. 2 is a perspective view of the vamp of Fig. 1, preshaped in accordance with a preferred procedure;

Fig. 3 is a fragmentary transverse section showing the completion of the step of assembling the upper with a sock lining or insole;

Fig. 4 is a similar view showing a welt strip assembled with and united to the upper and sock lining;

Fig. 5 is a similar fragmentary transverse section showing a last arranged within the upper and showing the welt strip turned outwardly and also showing the cushion sole in place;

Fig. 6 is a view similar to Fig. 5 but showing the outer sole assembled with and united to the other parts;

Fig. 7 is a fragmentary front elevation of the vamp of Fig. 2 illustrating the mode of crimping the vamp to impart prelasted shape thereto;

Fig. 8 is a side elevation of a completed shoe made in accordance with the present process;

Fig. 9 is a plan view, partly broken away, of a vamp for use in making a shoe in accordance with the present invention, the vamp including a toe stiffener;

Fig. 10 is a view similar to Fig. 9 but showing the vamp in readiness for assembly with the sock lining;

Fig. 11 is a fragmentary section similar to Fig. 3 but showing the toe portion of the shoe upper as comprising a stiffener element;

Fig. 12 is a fragmentary, diagrammatic view showing the forepart of a shoe in section and illustrating means useful in softening the toe stiffener;

Fig. 13 is a plan view, with parts broken away, showing a preferred form of sock lining; and

Fig. 14 is a longitudinal section through a shoe upper assembled with a sock lining showing the upper provided with both toe and heel stiffeners.

Referring to the drawings the numeral 1 indicates the vamp of a shoe, for example a child's shoe; while the numeral 2 (Fig. 8) designates the rear portion of the shoe upper, the parts 1 and 2 being shown as united by usual seams at 3. While one form of upper is here illustrated by way of example, it is to be understood that the upper may be of any usual type including as few or many parts as are usual to the particular type of shoe being made;

In accordance with the present invention it is preferred, although not essential, to impart to the toe portion 4 of the upper, that is to say to the vamp, a prelasted shape or contour generally similar to that of the toe portion of the last on which the shoe is to be lasted. Thus, as indicated in Figs. 2 and 7, the lower margin of the vamp at the toe portion thereof is shown as having been subjected to a crimping operation whereby the edge is contracted and gathered together as shown at 5, and at the same time the marginal material adjacent to this gathered portion is caused to take a convex curved contour. This contraction of the edge may be concomitant to the formation of stitches or result from the introduction of a gathering string or the like, although for simplicity it is preferred to produce this effect by a crimping operation in which the material of the upper is indented at closely spaced intervals so as in effect to shorten the edge of the upper and thus cause it to take a concave form;

In accordance with this invention there is provided an insole member 6 which is preferably by very thin material, for example textile fabric, and which is more aptly termed a "sock lining" since

this shoe resembles and is in fact a modification of the type of shoe known as a platform or California type shoe, or which is at times referred to as a "slip lasted" or "force lasted" shoe. Preferably, as illustrated in Fig. 14, the sock lining 6 comprises a textile ply 6^a, which is the upper or foot-contacting ply, and a ply 6^b of a material, for example paper, Cellophane, or other thin flexible material which does not easily stretch in any direction and which is adhesively united to the textile ply. Desirably, though not necessarily, the ply 6^b may be waterproof or moisture impervious. Whether or not the vamp is preshaped as above described, the lower margin of the upper (which may include a lining member 1^a, Fig. 3) is permanently united to the margin of the insole or sock lining 6. In thus uniting these parts, the margin 7 of the sock lining is turned downwardly (Fig. 3) and disposed against the inner surface of the lower margin of the upper and then these parts are united by suitable fastening means, for example adhesive, metallic fasteners or preferably by stitches of a seam 9 (Fig. 3). The union of these parts in this manner forms a rib 10 projecting beyond the plane of the sock lining 6 and defining a shallow cavity 11, the exposed edges of the united sock lining and upper being directed downwardly in the completed shoe.

While toe or counter stiffeners are not ordinarily used in children's shoes, they are desirable in many styles of shoe for adult wear. In accordance with the present invention, it is readily possible to introduce a toe or counter stiffener into a welt shoe of the herein described modified California or force-lasted shoe. Thus, as illustrated in Fig. 9, the vamp is shown as comprising a lining 1^a, an outer member 1 for example of leather, and a toe stiffener element 1^b of a thermoplastic material and which is interposed between the lining and outer member of the upper. The margin of the stiffener is skived or otherwise reduced to a thin edge, and the several plies are adhesively bonded together. The margins of the parts 1 and 1^a extend beyond the edge of the stiffener, and the projecting margins are crimped as shown at 5^a (Fig. 10) in the same way as above described with reference to the vamp shown in Fig. 2. The vamp including the stiffener is now assembled with the sock lining and united thereto as illustrated in Fig. 11. Before lasting, the toe stiffener is softened by the application of steam. As illustrated by way of example in Fig. 12, apparatus suitable for this purpose may include a steam conduit S provided with an upwardly directed hollow perforated post P over which the assembled upper and sock lining are drawn. The steam escaping from the perforations in the post P softens the thermoplastic stiffener element 1^b, and while it is still soft the lasting operation is performed.

If the shoe is to have a counter, the counter stiffener 2^b (Fig. 14) is introduced between the quarter 2 and the quarter lining 2^a before these parts are assembled with the sock lining, and the parts 2, 2^a and 2^b are then subjected to heat and moulding pressure to impart to the rear of the quarter a prelasted shape. The moulded quarter is then assembled with the sock lining and with the other parts of the upper before lasting.

The present invention contemplates the provision of a welt strip 12 which may be of any suitable flexible material, for example textile fabric, leather, or one of the synthetic materials which are now commonly used, for example in

making the ornamental welt strips used in stitch-down shoes. This welt strip may be of a width generally similar to that of the welt strip used in a Goodyear welt shoe and would usually have one finished surface. In assembling this welt strip with the sock lining and upper, the finished surface of the welt strip is disposed in contact with the outer surface of the upper, with one edge of the welt strip flush with the edge of the rib 10. The welt strip is then united to the upper material, preferably by fastener elements, for instance metallic fasteners or stitches, as indicated at 14, which pass into and preferably through the entire thickness of the rib material.

The last L is now introduced into the upper, thus distending the upper material and stretching the insole or sock lining 6 tautly in a substantially horizontal plane, as shown in Fig. 5. Either before or after the introduction of the last, the welt strip is turned downwardly and outwardly, as indicated at 15 (Fig. 5), so that the free marginal portion 16 of the welt strip is disposed to lie in the substantially horizontal plane defined by the edge of the rib 10. Within the cavity 11, defined by the sock lining 6 and the marginal rib 10, suitable filler material is placed. Thus for example a cushion or middle sole 17 may be provided, this cushion or middle sole preferably being of a soft, resilient material, for example felt, and this cushion sole is cut to shape and is of such thickness as substantially exactly to fill the cavity 11, the exposed surface 18 of the cushion sole, when thus disposed in position lying substantially in the same plane as the under surface of the portion 16 of the welt strip, thus providing a substantially flat, level exposed bottom surface. While the cushion sole 17 may be cut from sheet material of suitable thickness and to the proper shape to fill the cavity, it is contemplated that other types of filler material may be employed, for example plastic materials which may be placed in the cavity and leveled off so as to fill the latter and to provide a desired flat level bottom.

An outer sole 19 of any suitable material, for example leather, artificial leather, or the like, is provided and is laid onto the exposed surface 18 of the shoe bottom to which it may be united by cement 19^a or the like, if desired. This outer sole 19 may, if desired, be provided with a channel 20 to receive sewing stitches 21 by means of which the outer sole is secured to the portion 16 of the welt strip. The channel 20 is not necessary, although it may be preferred in making the more finished types of shoe, but if not provided, the stitches 21 will pass through the entire thickness of the outer sole and be exposed at its under surface. If the shoe is to have a heel, a heel wedge 22 may be secured to the rear part of the outer sole 19 after the outer sole has thus been stitched to the welt, in which event the heel member 22 may be secured to the sole member either by adhesive or by suitable fasteners, for instance nails or pegs. If preferred the heel member 22 may be first attached to the rear part of the sole member by adhesive, before the sole member is secured to the welt strip, and then the sewing stitches 21 will extend not only through the sole proper but also through the heel wedge 22.

While as above specifically described the invention is of particular utility in making children's shoes, it is to be understood that it is not limited to shoes of this kind but may be embodied in the manufacture of shoes of any desired size and of other types, for example slippers. It is

further to be understood that while a desirable sequence of steps has been indicated, this sequence may be varied if desired and equivalent steps substituted for those specifically suggested. It is also to be understood that any desired materials may be employed for the various parts of the shoe; that the lining ^{1a} may be omitted if desired; and that the welt strip may if desired be suitably shaped or treated before attachment to the shoe upper to facilitate disposal of its outer margin in the plane of the shoe bottom after its attachment to the upper.

I claim:

1. That method of making shoes which comprises as steps providing an upper and a sock lining, turning the margin of the sock lining downwardly and disposing it in contact with the inner surface of the lower margin of the upper, and uniting said margins by stitches to form a rib, providing a welt strip, sewing one margin of the welt strip against the outer surface of the lower margin of the upper by stitches which pass through the rib, introducing a last into the upper, filling the cavity defined by the sock lining and rib, thereby to provide a level bottom surface, turning the free margin of the welt strip outwardly so that its under surface is substantially in the plane of said level bottom surface, laying an outer sole upon said level surface, and permanently uniting the outer sole and welt strip.

2. That method of making shoes which comprises as steps providing an upper and a sock lining, turning the margin of the sock lining downwardly and disposing it in contact with the inner surface of the lower margin of the upper and uniting said margins by stitches to form a rib, providing a welt strip, sewing one margin of the welt strip against the outer surface of the lower margin of the upper by stitches which pass through the rib, introducing a last into the upper, providing a cushion sole of a contour and thickness such as to fill the cavity defined by the sock lining and rib, disposing the cushion sole in said cavity thereby to provide a level bottom surface, turning the welt strip downwardly and then outwardly so that the under surface of its free margin is substantially in the plane of said level bottom surface, providing an outer sole, cementing the outer sole to the cushion sole, and sewing the margin of the outer sole to the welt strip.

3. That method of making shoes which comprises as steps providing an upper, shaping the toe portion of the lower margin of the upper thereby to conform it generally to the shape of the toe portion of the last on which the shoe is to be lasted, providing a sock lining, turning the margin of the sock lining downwardly, and disposing it in contact with the inner surface of the

lower margin of the upper, and permanently uniting said margins thereby to form an inseam, providing a welt strip having a finished surface, placing one margin of the finished surface of the welt strip in contact with the outer surface of the lower margin of the upper, and permanently uniting the welt strip to the upper, introducing a last into the upper, turning the welt strip downwardly and outwardly so that its free marginal portion is substantially in the plane of the edge of the inseam, filling the cavity defined by the sock lining and inseam, arranging an outer sole to contact the edge of the inseam, and uniting the margin of the outer sole and welt strip by permanent fastener elements.

4. That method of making shoes which comprises as steps providing an upper and a sock lining, turning the margin of the sock lining downwardly and disposing it in contact with the inner surface of the lower margin of the upper and uniting said margins by stitches to form a rib, providing a welt strip, sewing one margin of the welt strip against the outer surface of the lower margin of the upper by stitches which pass through the rib, introducing a last into the upper, providing filler material to fill the cavity defined by the sock lining and rib, disposing the filler material in said cavity thereby to provide a level bottom surface, turning the welt strip downwardly and then outwardly so that the under surface of its free margin is substantially in the plane of said level bottom surface, providing an outer sole, cementing the outer sole to the filler material, and sewing the margin of the outer sole to the welt strip.
